UNITED STATES PATENT OFFICE

146,816

DESIGN FOR AN ARTICULATED ANIMAL FIGURE

Frank Larned Treuting, Newark, N. J., assignor
to Herbert R. Treuting, Sr., Newark, N. J.

Application August 14, 1946, Serial No. 132,516

Term of patent 14 years

(Cl. D34—2)

To all whom it may concern:

Be it known that I, Frank L. Treuting, a citizen of the United States, resident of the city of Newark, county of Essex, and State of New Jersey, have invented a new, original, and ornamental Design for an Articulated Animal Figure, of which the following is a specification, reference being had to the accompanying drawing, forming part thereof.

Fig. 1 is a side elevational view of an articulated animal figure, showing my new design.

Fig. 2 is a front elevational view of the articulated animal figure shown in Fig. 1, and

Fig. 3 is a rear elevational view of the articulated animal figure shown in Fig. 1.

Fig. 4 is a top view of the articulated animal figure shown in Fig. 1.

I claim:

The ornamental design for an articulated animal figure, as shown.

FRANK LARNED TREUTING.
